2,186,526

VALVE FOR BOTTLE FILLING MACHINES

Clement F. Greiner, London, England, assignor to
 The Liquid Carbonic Corporation, Chicago,
 Ill., a corporation of Delaware

Application November 30, 1938, Serial No. 243,105

4 Claims. (Cl. 226—115)

My invention relates to improvements in apparatus for filling containers with liquid.

More specifically, the invention relates to apparatus for filling containers with carbonated liquid and has particular reference to container filling apparatus wherein initially pressure is admitted to the container slightly less than the pressure tending to deliver the liquid to the container whereby the liquid will be slowly delivered into the container. After a proportion of the liquid has been delivered to the container, the pressure in the container is reduced to such an extent that the liquid will flow therein more rapidly.

In filling containers with carbonated beverages and particularly in filling containers with beer, it is extremely desirable that all air be exhausted from the container prior to the delivery of beer thereinto and it is further desirable that in the filling operation, air be excluded from the container to reduce danger of spoilage or deterioration of the contents to the minimum.

My invention relates primarily to means whereby with the above type of filling machines, the air normally in the container prior to the filling operation, may be exhausted therefrom and to provide means whereby no additional air, even during the filling operation, will be admitted to the container.

For the purpose of disclosing my invention, I have illustrated an embodiment thereof in the accompanying drawings, in which:

Fig. 1 is a longitudinal sectional view of so much of a filling apparatus as is necessary for the understanding of my invention;

Fig. 2 is a longitudinal sectional view of the filling valve;

Fig. 3 is a top plan view of the stator of the counter pressure controlling valve; and

Fig. 4 is a bottom plan view of the stator of the vacuum controlling valve.

In the structure illustrated, I provide a rotary head 1 carrying the usual plurality of vertically movable container elevating platforms 2. This head also is provided with a supporting cylinder 3 having an annular platform 4 carrying the annular tank 5 in which the liquid to be delivered to the container is maintained. This filling tank 5 is provided with a plurality of filling valves 6, each of which is adapted to contact with and deliver to the liquid from the tank 5 a container moved into contact therewith by the elevating platform 2. There may be as many as desired of these filling valves and container supporting platforms and in the particular struc-

ture illustrated, I provide as high as forty valves. Each of these valves is of the same construction and is adapted, during the rotation of the machine, to contact and fill a container. The liquid to be delivered to the containers is supplied to the tank 5 through a suitable supply pipe 7 connected with the main source of supply of the liquid and the liquid is periodically delivered to the tank 5, in accordance with the demands on the tank and in sufficient quantities to maintain the level of the tank substantially constant. As each of the filling valves is of exactly the same construction, a description of one will be sufficient.

Each of the valves is provided with a base 8 adapted to be secured within a suitable opening in the bottom of the tank 5. This base supports a filling tube 9 adapted to be projected into the container to be filled to a point slightly spaced from the bottom thereof and the bottom of this tube is normally closed against egress of the liquid by a pear-shaped valve 10. The pear-shaped valve is opened and closed by an operating stem 11 which projects upwardly through the filling tube 9 and is connected at its upper end to a diaphragm 12 operating in a pressure chamber 13 formed between a head 14 and the diaphragm. This head is clamped upon a casting 15 between the peripheral edges of which and the peripheral edges of the head 14, the diaphragm is secured. A neck 16 extends downwardly from the base 8 and is provided with a pressure chamber 17 which communicates with a comparatively short pressure tube 18 secured in the neck. Surrounding this pressure tube is a valve seat 19 receiving a rubber gasket valve 20 biased in its closed position by a coiled spring 21. Pressure is admitted to the chamber 17 through an opening 22 in a boss 23, the connection of which will be more fully described hereinafter. Extending upwardly from the base are a plurality of conduit tubes 24 communicating with the pressure chamber 17 by passages 26 and these tubes communicate with the chamber 13 above the diaphragm 12 by ports or passages 25.

Slidably supported on the filling tube 9 is a housing 27 having a bell mouth 28 adapted to engage the container and provided with a sealing gasket 29 adapted to engage the neck of the container and seal the same at this point. The upper portion of this housing 27 is provided with a pressure chamber 30 and at its top, this housing is provided with a seat 31 adapted to receive the lower end of the tube 18 and with the seat 55

32 adapted to engage a sealing gasket 33 at the lower end of the neck 16. In operation, as the container is raised into engagement with the gasket 29, the housing 27 is raised with the container on its upward movement until the seat 32 contacts the gasket 33. At the same time, the lower end of the tube 18 engages the seat 31 making a sealing contact therewith and the upward movement of the housing 27 raises the valve 20 off of its seat admitting pressure to the pressure chamber 17 which pressure passes down through the tube 18 through the chamber 30 and into the container. As the pressure in the container builds up, this pressure eventually builds up through the passages 25, the tubes 24 and in the pressure chamber 13 above the diaphragm 12, thereby exerting sufficient pressure on the diaphragm 12 to force the stem 11 downwardly opening the valve 10 to permit the liquid to flow from the tank 5 into the container.

The supporting cylinder 3 carries a water check tank 34 adapted to rotate with the parts heretofore described and having a top 35 provided with a central portion comprising a rotor 36. Within the water check tank 34 is provided a pair of cylinders 37 and 38 supported from the head 35 and the top of the cylinder 38 comprises a counter pressure stator valve 39. This stator valve 39 is provided with a port 40 extending to a groove 41 in the stator 39 and communicating with the cylinder 37. A second port 42 extends to a groove 43 in the face of the stator and this port communicates with the cylinder 38.

The rotor 36 on the head 35 is provided with a series of ports 44, one for each of the filler valves heretofore described and each adapted to be connected by the pipe 45 with a boss 23 of the filler valve. Mounted above the rotor valve member 36 and cooperating therewith is a vacuum valve stator 46 having a port 47 therein connected by a pipe 48 with any vacuum producing means.

It is to be noted that this port 47 communicates with a groove 49 in the face of the stator and that this groove during the rotation of the rotor 36, at proper timed intervals, communicates with the respective ports 44 of the rotor 36.

Pressure, preferably in the form of carbon dioxide under pressure, is admitted to the water tank and the respective cylinders 37 and 38 through a tubular coupling 50 which extends through a neck 51 in the stator head 39 to communicate with the interior of the tank 38. This tubular supply member has a suitable connection, as at 51', with a pressure supply, preferably carbon dioxide under the desired pressure. The water check tank 34 has a connection 52 with the tank 5 whereby the pressure in the tank 5 and the water check 34 is equalized. In order that the stator head 46 may be held stationary, this head is keyed, as at 46', to the tubular coupling 50. This tubular coupling 50 extends through and is keyed to, as at 50'', a stationary sleeve 51''. This sleeve has connected to it an anchoring rod 51' which, in turn, is anchored to a stationary stand 51''. The coupling member 50 is thus anchored against rotation and with it, the head 46. The stator head 39 is likewise held against rotation, it being clamped upon the tubular coupling 50 and if desired may be keyed thereon.

The water check tank 34 is provided with a suitable supply of water. Pressure, preferably in the form of carbon dioxide, is admitted to the cylinders 38 and 37 forcing the water out of the cylinders 38 and 37 and creating sufficient pres-

sure to maintain the water level in the tank 34 at a predetermined point with both of the cylinders 37 and 38 empty. As a result, due to the increased length of the cylinder 38, a higher pressure is exerted in cylinder 38 than in cylinder 37. 5

As the cylinder 3 and associated parts is rotated carrying with it the rotor head 36, the groove 49 will be moved to coincident relationship with the port 44 of the rotor 38, thereby placing the pipe 45 in communication with the pipe 48. The 10 container having already been moved into sealing contact with the sealing gasket 20 and thereby raising the tube 18, the valve 20 will be opened, thus placing the container in communication with the vacuum producing means and as a result for the period of time it takes for the port 40 to rotate past groove 49 a vacuum will be produced in the container to be filled, thus exhausting all of the air therefrom. The continued rotation of the rotor 36 will then place the port 20 15 44 into communication with the groove 43 thereby placing the high pressure cylinder 38 in communication with the container to be filled. The pressure in this chamber is slightly less than the head, tending to cause the liquid to flow out of the 25 tank 5. After this pressure has built up in the container, it will build up in the diaphragm 13, as heretofore described, thereby causing the liquid valve 10 to be opened and the liquid is admitted from the tank 5 into the container against 30 this "high pressure" in the container. Due to the fact that this "high pressure" is only slightly less than the liquid head in the tank 5, the liquid in the tank will slowly flow into the container until it approximately reaches the level of the 35 bottom of the tube 9. By this time, the port 44 will have passed out of communication with the groove 43 and into communication with the groove 41, thereby placing the container into communication with the "low pressure" cylinder 40 37. The pressure in this cylinder is less than the pressure in the cylinder 38, therefore the liquid will flow from the tank 5 into the container at an accelerated rate and will continue to flow until the head of the liquid in the tank 5, plus the 45 pressure above this head, is equal to the pressure in the cylinder 37, at which point the liquid ceases to flow, due to the equalization of pressures, and the container will have become filled. After the container has become filled, the support 2 begins its downward movement, first closing the valve 20 and shutting off any pressure to the container and eventually breaking the seal between the tube 18 and its seat 32. With the pressure shut off by the valve 20, any pressure 55 in the chamber 17 will exhaust through the bleed openings 53, thus reducing the pressure in the chamber 13 and permitting the pressure in the tank to act against the under side of the diaphragm to close the valve 10, thus shutting the 60 tube against the escape of any liquid therein.

I claim as my invention:

1. The combination with a filling tank, of a plurality of filling tubes associated with said tank and supplied in a cycle, a pressure 65 tank having a plurality of pressure chambers therein, a stator associated with said pressure tank having ports therein, one for each of said chambers, a rotor having ports therein, one for each of said filling tubes and adapted to coincide 70 in seriatim, respectively, with the ports in said stator, and a second stator having a port therein connected with a vacuum producing source and adapted to successively coincide with the ports of said rotor.

2. In a container filling machine, the combination with a rotary filling tank, of a plurality of filling valves associated therewith supplied therefrom in a cycle, a pressure tank adapted to rotate with said filling tank and having a plurality of pressure chambers, a stator valve member associated with said chambers having ports communicating therewith, one for each chamber, a valve rotor associated with said stator having a plurality of ports therein, one for each of said filling valves, each port being adapted to successively coincide with the stator ports and a second valve stator having a port connected to a vacuum source and adapted to successively coincide with said rotor ports.

15 3. In a container filling machine, the combination with a rotary filling tank, of a plurality of filling valves associated therewith supplied therefrom, a pressure tank associated with said liquid tank having a plurality of pressure chambers therein, a head closing said pressure tank, said head having a plurality of ports therein connected to said valves, one for each of said valves, a stationary valve member arranged within said

20 tank having a plurality of ports therein, one connected to each of said chambers and adapted

25 during the rotation of said pressure tank to coincide with the ports in the head thereof, and a second valve member cooperating with said head having a port therein connected with a source of vacuum, said port being adapted to successively coincide with the ports in said head.

4. In a filling machine, the combination with a rotary filling tank, of a plurality of filling valves associated therewith and supplied therefrom, a pressure tank adapted to rotate with said filling tank having a plurality of pressure chambers therein, a head for said pressure tank having a plurality of ports, one for each filling valve connected with said valves, a relatively stationary pressure supply stem extending through said head, a stator valve member mounted on said stem and having a plurality of ports, one for each of said pressure chambers and adapted to successively coincide with said first-mentioned ports, and a second stationary valve member surrounding said stem and cooperating with said head having a port connected with a vacuum producing source, said port being adapted to successively coincide with the ports in said head.
